UNITED STATES PATENT OFFICE.

ANDREW G. BRANDT, OF SCRANTON, PENNSYLVANIA.

THILL-CO尤LING.

SPECIFICATION forming part of Letters Patent No. 317,084, dated May 5, 1885.

Application filed March 10, 1885. (No model.)

To all whom it may concern:

Be it known that I, A. G. BRANDT, of Scranton, in the county of Lackawanna and State of Pennsylvania, have invented certain new and useful Improvements in Thill-Couplings; and I do hereby declare the following to be a full, clear, and exact description of the same, reference being had to the accompanying drawings, forming a part of this specification, and to the figures and letters of reference marked thereon.

My invention relates to improvements in devices for preventing the disagreeable rattle of the thill-couplings on a vehicle; and it consists of a certain improved construction, which I will now proceed to describe.

In the accompanying drawings, Figure 1 is a view showing the application of my invention to the thill-coupling of a vehicle. Figs. 2 and 3 are detached views of the same.

Similar letters of reference in the several figures denote the same parts.

A represents the axle of the vehicle to which my invention is applied, and B the bed of the same.

C represents the clip used for connecting the thills to the axle, the same consisting of the portion C' for extending over the axle, and provided with the two lugs D D, between which the end of one of the thills is secured by means of the bolt E, passing through them and through the perforated end of the plate F, secured to the thill. The screw-threaded bolts C' C' of the portion C' project through the plate G, and are provided with the nuts g g for clamping the whole device securely to the axle.

The foregoing is simply a description of the ordinary device employed for connecting the thills of a vehicle to the axle, and forms no part of my invention.

My improved anti-rattler consists of a spring-steel plate, H, bent into the form shown—that is to say, formed with the loop I, and bent portion I' just below the said loop, substantially conforming to the shape of the thill-plate, the straight portion I', and the two depending legs J and K, the former being slightly shorter than the latter, and having at its lower end the short curved portion i. The two legs J and K are placed at a slight angle to the rest of the spring, as shown.

Co-operating with the spring H is a metal

plate, L, having near one of its ends a series of perforations or slots, l l' l'', in one of which the short leg of the portion H is adapted to be inserted. The tendency of the legs of the spring H is to press toward each other, and therefore when the end of the leg J is inserted into one of the series of perforations l in the plate L the resiliency of the spring will hold the two plates together, the curve i preventing the plate from slipping off.

When the device is to be applied to the thill-coupling of a vehicle, the plate L is placed in the position shown in Fig. 2, substantially in line with the legs of the spring, and is inserted into the space between the lugs D D and the thill-plate and clip, as shown, and is prevented from dropping through by the loop I. The plate L is moved into the position shown in full lines in Fig. 1, separating the two legs of the spring portion and forcing the thill against the transverse bolt of the coupling, thus effectually preventing any rattling. The end of the leg J being curved at i prevents the plate L from slipping off, and also serves as a fulcrum of the latter, so that the longer leg K, pressing upon its end, will keep it at all times up against the nuts g g and prevent them from working off, thus forming a nut-lock.

The several slots in the plate are for the purpose of making the spring of the same tension at all times. Thus when it has lost some of its resiliency from any cause the end i can be moved from the slot l to slot l' or l'', causing the legs to separate more, and this adjustable feature also admits of the use of my invention on vehicles having clips and thills of different sizes.

It will be seen from the above construction that my invention is admirably adapted for the purpose, consists of very few parts, can be manufactured cheaply, and can be applied to any vehicle in use, dispensing with the services of a skilled mechanic, which are necessary in the application of most of the anti-rattlers now in use. It will also be seen that the application of the device will not prevent the shafts from being raised up to any height necessary or desirable.

I claim as my invention—

1. The combination of the spring, looped and having the depending legs, as described, with

the plate having the perforation near its end, through which one of the legs of said spring portion projects, so that when said plate is moved in one direction the two legs of the 5 spring will be separated, and when moved in the opposite direction it will fold substantially in line with the legs, as set forth.

2. The combination, with the spring having the loop and the two depending legs, one of 10 which is shorter than the other, of the plate having the slot near one of its ends, through which the shorter leg of the spring projects, as set forth.

3. The combination, with the spring having 15 the loop and two depending legs, one of which is shorter than the other and has its end slightly bent, as shown, of the plate adapted to co-operate with said spring portion having a

slot near one of its ends, through which the end of said shorter leg is inserted, as set forth. 20

4. The combination, with the spring having the loop and two depending legs, of the plate for co-operating with said spring provided with one or more slots or perforations, substantially as described. 25

5. The combination, with the spring having the loop I, the straight portion I², bent portion I', and depending legs J and K, of the plate L for co-operating with said spring, having the perforation or slot near one of its ends, substantially as described. 30
